UNITED STATES PATENT OFFICE.

JOHN T. SKINNER, OF LAWRENCE, KANSAS.

ALTERNATING-CURRENT ELECTROMAGNETIC CONTROL-SWITCH.

1,230,934.

Specification of Letters Patent. Patented June 26, 1917.

Application filed January 28, 1915. Serial No. 4,856.

To all whom it may concern:

Be it known that I, JOHN T. SKINNER, a citizen of the United States, residing at Lawrence, in the county of Douglas and State of Kansas, have invented certain new and useful Improvements in Alternating-Current Electromagnetic Control-Switches; and I do declare the following to be a full, clear, and exact description of the invention, such as will enable others skilled in the art to which it appertains to make and use the same.

This invention relates to electro-magnetic switches but more particularly to those used in conjunction with an alternating current and adapted to control auxiliary or branch circuits of motors, lamps, etc., located at points remote from the switch.

One object of this invention is to provide an electro-magnetic switch of the character specified which is simple in construction, inexpensive to produce, and silent in operation.

Another object of this invention resides in providing an electro-magnetic switch controlled by an alternating current and having means to compensate for the vibratory movement conveyed to the various working parts of the switch by reason of the pulsating current employed to operate the same.

Another and still further object of this invention is to provide a switch which may be used in a high tension circuit and have ample means to insulate the controlled from the controlling circuit.

Another and still further object of this invention resides in providing a switch having the parts thereof so balanced as to enable the operation thereof with a minimum amount of current.

Another and still further object resides in providing novel means for yieldably mounting the solenoids and the switch contact of the controlled circuit.

With these and other objects in view, the invention consists of certain novel features of construction, and the combination and arrangement of parts as will be more fully described and claimed.

In the accompanying drawings, in which

corresponding parts are indicated by similar reference characters,

Figure 1 is a front elevation of my improved switch with the front portion of the casing removed, certain of the parts being shown in section;

Fig. 2 is a transverse vertical section taken on the line 2—2 of Fig. 1;

Fig. 3 is an enlarged vertical section taken on the line 3—3 of Fig. 1;

Fig. 4 is a transverse vertical section taken on the line 4—4 of Fig. 1.

In controlling electric circuits especially street lights, and park and boulevard lighting systems, etc., at points where a high voltage series line would be objectionable, patrol service too expensive and time switches expensive, annoying and undesirable, where these points are within a convenient distance of an established alternating circuit, it is frequently desirable to employ a series control device for such systems, which is positive and reliable in action as well as one capable of being maintained at a comparatively low cost. In many instances such a device would save considerable first cost of construction, inasmuch as while low voltage conduits could be carried from the established alternating circuit in the immediate vicinity of the switch to the latter at a very small expense, the construction of a high voltage series loop to and from the lamps or circuit desired to be controlled, would be extremely impractical, therefore, it is to this end that I have provided the switch under consideration by means of which electric circuits of motors and lamps, etc., may be conveniently controlled by means of a very small amount of alternating current.

Referring more particularly to the illustrative embodiment of my invention, 1 comprises a casing of rectangular formation preferably constructed of metal. This casing is formed in two parts to wit: A front 1' and a back 1'', the former being detachably connected to the latter in any suitable manner. The front 1' is provided near the top and bottom thereof with openings 1''' by means of which the casing may be ventilated. In order that the casing may be read-

ily adapted to any support or may depend therefrom as demand requires, said casing is provided with apertured attaching ears 3 through which suitable fastening elements 5 may be passed. Within the casing 1 is a substantially rectangular frame 4 mounted centrally with respect to the casing, upon bolts 5 which pass through the frame 4 and engage seats 6.

10 Centrally arranged within the frame 4 are two U-shaped brackets 7 whose horizontal legs are disposed in opposite directions and whose vertical portions are arranged in parallel and spaced relation, said 15 horizontal legs being attached to the top and bottom of the frame 4 by suitable fastening elements. Extending in horizontal planes are two pairs of supporting bars 8, one upper and one lower, said bars being 20 formed of insulating material and the respective pairs thereof disposed in vertically spaced relation. To support the free ends of the bars 8, the frame 4 is provided with laterally extending shelves 9 which are apertured 25 at their outer ends to receive the bolts 10 passing transversely through the bars 8 and the openings formed in the shelves 9, said bolts being retained in position by ordinary retaining nuts. Vertically disposed 30 between the bars 8 at a point central thereof, is a rod 12 whose upper end passes through a suitable opening formed in the auxiliary guide plate 12' which extends transversely across the central portions of the uppermost 35 pair of bars.

Extending transversely across the lowermost pair of bars 8 are two contacts 13, one of said contacts being disposed on each side of the rod 12 as clearly shown in Fig. 1. 40 In order to provide connecting means for the terminals of the controlled circuit, these contacts 13 have their ends extended as at 14 so as to project beyond the bars, and the ends thus extended are provided with 45 binding posts 15 as clearly shown in Figs. 1 and 2.

Disposed upon the rod 12 is a sleeve 16 whose lower end rests upon a washer 17 which is supported by a laterally projecting 50 stud 18 on the rod 12. The upper end of the sleeve 16 supports a washer 19, upon which rests an annular copper plate 20, the function of which is to bridge the contacts 13 and control the remote circuit as will 55 be readily understood. The sleeve 16 is made of insulating material to provide insulating means for the rod 12 should the same accidentally come in contact with the contacts 13. To yieldingly maintain the 60 copper plate 20 in engagement with the washer 19 a spring 21 is interposed between a washer 22 and a washer 23 resting on the upper surface of the bridging plate 20 and in this connection it will be seen that the

upper washer 22 is prevented from moving 65 by the laterally projecting stud 23' carried by the rod 12.

The purpose of the foregoing structure, is to enable the rod 12 which carries the contact plate 20 to vibrate without disturbing 70 said plate, when the latter is in engagement with the two contacts 13 as will be readily understood without further description.

Extending through the vertical portions of the bracket 7 contiguous to the lower ends 75 thereof, is a bolt 24 which is held in place by a fastening nut 25. Pivotaly mounted intermediate of its ends upon said bolt 24 and between the bars 8, is a lever 26 formed of insulating material. The central portion 80 of the lever 26 is reduced and provided with metallic side pieces 27 which enable it to move freely upon the bolt 24 with a minimum amount of friction. The extremities of the lever 26 are also reduced and provided with clips 28 which latter carry transverse pins 29 and 30. To engage the pin 29 the rod 12 has its lower end apertured so that said pin 29 may pass therethrough and thus pivotally connect one end of the lever 90 26 to the lower end of the rod 12 for a purpose to be hereinafter set forth.

Projecting through the top of the frame 4 in spaced relation are four pins or pivot bolts 31 and to the free end of each of said 95 bolts is secured a link 32 having a transverse pin at the lower extremity thereof. Between each pair of the links 32 is arranged a resilient strip 33, the extremities of said strip being engaged with the transverse pins carried by said links 32. A pair of solenoids 34 having insulating end pieces 34' are secured to the strips 33 by the bar 34'' which is suitably secured to the central portion of the upper end piece of solenoids 34 and has 105 its extremities connected by rivets or otherwise to the central portion of the resilient strips 33. By connecting the solenoids in this manner, it will be seen that the same are yieldably supported by the bolts 31. The 110 lower insulating end piece 34' intermediate its ends has formed thereon a lateral extension 34''' which is provided with an opening adjacent the free end thereof. This extension as will be seen by referring to Fig. 1 115 of the drawings, projects toward the inner side of the frame 4 for a purpose hereinafter to appear. Secured to one side of the frame adjacent the extended end of the solenoids 34 is a U-shaped bracket 35 having its upper and lower legs projecting inwardly from the side of the frame and extending above the extended apertured end of the solenoids 34. The upper and lower legs of the bracket 35 are apertured, which apertures register with that in the extended end piece of the solenoids 34 so that a pin 36 120 125 may pass through the apertures in the legs

of said bracket and extend through the end piece of said solenoid. To yieldably retain the extension 34 in a central position upon the bolt 36, two springs 37 are provided as clearly shown in Fig. 1. Furthermore, as it would be undesirable to have any current reach the frame 4, the bracket 35 is insulated from the latter by a suitable insulating material.

From the above it will become apparent that any vibration due to the alternating current employed to energize the solenoids 34, will be readily permitted by reason of the yieldable mounting hereinbefore described. Each of the electro-magnets 34 is provided with a centrally arranged longitudinally extending annular opening 38 having therein a thin smooth non-magnetic tube 39. A U-shaped laminated plunger 40 has one of its legs disposed in each of the tubes 39 in the solenoids 34 so that whenever said solenoids are energized, the plunger will be drawn upwardly as will be readily understood without further description. To the intermediate portions of the horizontal part of the plunger 40 is connected the yoke-shaped resilient plate 41. Passing through the horizontal leg of the plates 41 is a bolt 42 having a transverse opening at its lower end through which passes a pin 43, this pin 43 pivotally supporting the link 44 which latter carries at its free end, a transverse pin 45 which extends through the apertured end of the rod 46, the lower end of said rod being also apertured to receive the pin 30 carried by the free end of the lever 26. Hence when the solenoids 34 are energized their plungers will be drawn upwardly, which will of course actuate the rod 46 and thus elevate one end of the lever 26 so as to bring the contact plate 20 into engagement with the two contacts 13 and project the same.

On the same side of the frame 4 as the U-shaped bracket 35 and immediately below the latter, is a terminal plate 47 having binding posts 48 and 49, said terminal plate being properly insulated from the frame 4 to prevent short circuiting of the current as will be readily understood. Also secured to this side of the frame 4 immediately above the terminal plate 47 is another terminal plate 50 having binding posts 51 and 52. The bottom of the frame 4 is formed with a series of spaced openings which register with similar openings formed in the bottom of the casing 1, and within these openings are disposed insulating sleeves 53. Passing through the sleeves 53 are the four conductors 54, 55, 56 and 57. The conductors 56 and 57 extend from the controlled circuit and have their upper ends connected to the binding posts 15 on the contacts 13, while the conductors 54 and 55 extend from

the controlling circuit and are connected to 65 the binding posts 51 and 48 respectively.

In order to convey the current to the solenoids 34, a conductor 58 has one end connected to the binding post 49 and the other to one terminal of one of the solenoids 34, 70 while the other terminal of said solenoids is connected by a conductor 59 to binding post 52 on the terminal plate 50.

From the above connections it will be apparent that alternating current coming from 75 the source of supply through the conductor 54 will be conducted to the terminal plate 47 and thence through the conductor 58 to the solenoids 34; from these it will be carried by the conductor 59 to the terminal plate 50 and 80 from the latter by conductor 55 to the source of supply. This alternating current will energize the solenoids 34, actuate the plunger and bring the annular metallic plate 20 into contact with the two contacts 13; to thus 85 close the controlled circuit so that current may flow through the conductor 56, contact 13, plate 20, and return to conductor 59, all of which will be apparent on referring to Fig. 1 of the drawings. To prevent the one 90 end of the lever 26 from violently contacting with the bottom of the frame 4, a rubber bumper 60 is disposed immediately below the lower end of the rod 46.

Thus, it will be seen that the rod 46 and 95 rod 12 together with its contact plate, and means for yieldably supporting the same, are approximately balanced, and that the weight of the plunger is just sufficient to maintain the plate 20 in disengaged position 100 when the solenoids 34 are deenergized, so that the solenoids 34 instead of being compelled to actuate the switch, simply has to lift its plunger, and the contact plate 20 will be lowered so as to close the controlled 105 circuit. In other words, the rod 12 together with the plate 20 and means for supporting the same are heavier than the rod 46 without the weight of the plunger 40. This means that the movable parts of the switch may be 110 actuated by means of a very small amount of current, in fact only such current as would be necessary to lift the plunger of the magnet.

Thus it will be seen that I have provided a switch which is very simple yet extremely 115 efficient, and one which will be certain in operation under all conditions.

Although in the foregoing I have described certain elements as best adapted to perform the functions ascribed to them, nevertheless it is to be understood that various changes as to form, substance, etc., may be resorted to within the scope of the appended claims without departing from or sacrificing any of the principles of the invention.

I claim:

1. A device of the class described com-

- prising a casing, a pair of U-shaped brackets arranged within said casing, the legs of said brackets extending horizontally in opposite directions and being secured to the top and bottom of the latter, the intermediate portions of said brackets being arranged vertically, vertically spaced pairs of upper and lower horizontal supporting bars secured at one of their ends to the vertical portions of 10 said brackets and having their other ends secured to one side of said casing, a guide plate extending transversely across the central portions of the upper supporting bars and having an opening therein, a pair of 15 horizontally spaced contacts extending transversely across the lower supporting bars, a vertically disposed rod slidably received at its upper end in the opening in said guide plate and having its lower end 20 disposed between said contacts, a contact bridging plate carried by said rod, and means for actuating said rod.
2. A device of the class described comprising a casing, a pair of spaced parallel horizontal resilient strips secured at their extremities to the top of said casing, a bar se-

cured at its extremities to the central portions of said strips, a vertically disposed solenoid connected at its upper end to the central portion of said bar, and a plunger 30 for said solenoid.

3. A device of the class described comprising a casing, a vertically disposed solenoid movably connected at its upper end to the top of said casing, a lateral extension at 35 the lower end of said solenoid and having an aperture therein, a bracket attached to one side of said casing and having a pair of legs projecting horizontally and in vertically spaced relation therefrom, a pin arranged 40 vertically between said legs and fixed thereto, said pin extending through the aperture in the solenoid extension, coiled springs surrounding said pin above and below the latter, and a plunger for said solenoid. 45

In testimony whereof I have hereunto set my hand in presence of two subscribing witnesses.

JOHN T. SKINNER.

Witnesses:

HUGH MEANS,
L. N. LEWIS.
